ADJUSTABLE PITCH PROPELLER

Frank W. Caldwell, Pittsburgh, Pa., assignor, by
mesne assignments, to United Aircraft Corpora-
tion, a corporation of Delaware

Application April 21, 1931, Serial No. 531,685

27 Claims. (Cl. 170—163)

This invention relates generally to propellers for aircraft, and more particularly to mechanism for automatically controlling and changing at will the pitch of the blades while the propeller is operating.

While controllable pitch propellers for aircraft have been proposed before, and some experiments have been made with devices intended to control pitch adjustment, most propellers have been constructed in such manner that the pitch angles of the blades can only be adjusted by mechanics on the ground. When the pitch angle of a propeller cannot be modified while the aircraft is in flight, the pitch angle at which the propeller is set is necessarily selected as a compromise between the angles most efficient for flight under various conditions. For example, it is desirable that a propeller should be adjusted to low pitch during the take-off period. During it the airplane necessarily moves at relatively low speed through the air, with heavy load on the propeller, and consequently, if the pitch of the propeller is too high, the resistance offered by the air to rotation of the propeller will be such as to hold the engine to a comparatively low speed. Engines do not develop maximum power at low speeds, and therefore, with a high-pitched propeller, the engine is most inefficient in the period when greatest power is needed.

If on the other hand, the propeller is adjusted to a low-pitch position during the take-off period, offering minimum resistance to rotation, the engine will be able to drive the propeller at normal engine speed, or somewhat above normal speed, and a quick short take-off and rapid elevation are possible.

After the take-off has been completed, and the plane assumes its normal level flight, the speed of the plane through the air is considerably increased, the resistance to propeller rotation is decreased, and the engine will speed up. To avoid over-speeding, it is then necessary to throttle the engine down to normal speed. The engine will then be producing only a portion of the power of which it is capable.

During level flight, it is desirable that the propeller be adjusted to high-pitch position so that it will absorb all of the available power of the engine, offering sufficient resistance to hold the engine to its normal full-power speed with efficient operation of the propeller.

It is therefore an object of my invention to provide a propeller for aircraft having blades the pitch of which may be controlled during flight of the aircraft. Another object is to provide a

propeller which may be adjusted by manually controlled means to low-pitch position during the take-off period of flight, and readily changed by automatic constantly-operative centrifugally-actuated means to high-pitch position after the aircraft has attained normal level flight. Another object is to provide a controllable pitch propeller which may be moved and held in low-pitch position by fluid pressure means, and later allowed to move to high-pitch position by the action of centrifugal force on a counterweight mechanism, upon release of the fluid pressure. A further object is to provide a controllable pitch propeller that will continue to operate as a fixed pitch propeller in the event of any accident to the adjusting mechanism.

An object of the invention is to provide automatic control mechanism for a controllable pitch propeller whereby the pitch may be regulated in response to changes in the engine speed, to maintain the speed of the engine substantially constant. A further object is to provide a controllable pitch propeller having adjustable limit stops to define a low-pitch position and a high-pitch position.

A further object is to provide improved methods of making and assembling controllable pitch propeller mechanisms.

In accordance with this invention I provide a propeller having blades journaled to turn about their longitudinal axes for pitch-changing, but fitted tightly to the hub to reduce to a minimum relative motion therebetween during normal operation. Linkage is provided for moving the blades, and adjustable limit stops define the low-pitch and the high-pitch positions. Fluid pressure means, suitably connected to the linkage, move the blades to low-pitch position, as during the take-off period, and counterweights are provided for constantly urging the linkage, by centrifugal force to move the blades to high-pitch position, the counterweights being effective when pressure is released from the fluid pressured operated means. Governing means are provided, operatively connected to the fluid pressure system, by which it is possible to automatically adjust the pitch of the propeller during flight in response to variations in the speed of the engine, to maintain the engine speed substantially constant at a speed to give most effective propeller operation.

In the accompanying drawings, Fig. 1 is a view in longitudinal section of a controllable pitch propeller embodying my invention, taken on the plane represented by the line I—I of Fig. 2, and showing, partly in section and partly

diagrammatically, a fluid pressure control system for operating it; Fig. 2 is an enlarged view, in longitudinal section, of the propeller shown in Fig. 1, taken on a plane at right angles to the plane of section thereof and represented by the line II—II; Fig. 3 is a view similar to Fig. 2, showing the propeller in elevation with the blades broken away and a modified fluid pressure control mechanism partly in longitudinal section and partly diagrammatically; Fig. 4 is a view in longitudinal section, similar to Fig. 2, of a modified propeller blade shank and thrust bearing therefor; Fig. 5 is a diagrammatic representation of a blank for a hollow steel propeller blade showing a method of applying a thrust bearing to it; Fig. 6 is a representation of a completed hollow steel propeller blade with the thrust bearing in operation position; Fig. 7 is a view in longitudinal section of the governing device shown in Fig. 3 for controlling the fluid pressure system; Figs. 8, 9 and 10 are views in cross section of the governor, taken on the planes represented by the lines VIII—VIII, IX—IX and X—X, respectively, in Fig. 7; and Fig. 11 is a graphical representation of the various twisting moments that act upon the propeller blades.

Referring more particularly to Figs. 1, 2 and 3 of the drawings, a controllable pitch propeller embodying my invention comprises, in general, a hub structure 1 upon which is mounted a plurality of propeller blades 2, extending from the hub 1 in the plane of rotation and with their axes in alignment. The hub 1 is carried, in the usual manner, on the end of a hollow engine shaft 3, protruding from a crank case 4. The end of the shaft 3 is tapered to fit a complementary tapered bore in the hub 1, and the exterior of the shaft is splined to mate with a similarly splined interior surface of the hub. The hub 1 is held on the shaft 3 by a retaining nut 5 that engages threads on the end of the shaft and bears against the forward end of the hub.

The hub 1 is a one-piece structure comprising in general a substantially cylindrical body portion from which extend integrally formed arms 6 to constitute a spider having studs on which the blades 2 are mounted. The particular blades 2 shown in the drawings are similar to conventional metallic blades insofar as their general shape and aerodynamic qualities are concerned.

The roots or shanks of the blades are hollow, and each blade root is bored, and fitted with an internal sleeve 11 having internal bearing surfaces 12 and 13 that engage complementary journals on the arms 6. The bearing surfaces on the arms function to transmit driving torque to the blades and permit them to be turned about their longitudinal axes for adjusting the pitch. The sleeve 11 is provided with an integral laterally extending flange 14 that abuts against the end of the blade 2 and is provided with a laterally disposed bearing surface 15 that engages a complementary annular plane bearing surface 16 on the body portion of the hub 1 encircling each stud 6 to cooperate with the stud in rigidly holding the blade 2.

The end of the blade adjacent the flange 14 is provided with an integral outwardly turned flange 21 to which the flange 14 is secured by dowels or screws 22. For holding the blades 2 on the studs 6 with the flanges 14 tightly against the bearing surfaces 16, each blade is provided with an anti-friction thrust bearing 23 disposed to encircle the blade shank and to bear against the outwardly turned flange 21. The bearings

23 on the two blades are inter-connected by a thrust resisting structure or barrel 24, having, at its ends, inwardly turned flanges 25 that engage the outer races of the thrust bearings.

As shown, the barrel 24 is split along its longitudinal axis in such manner that it may be fitted over the blade roots and the semi-cylindrical halves secured together by suitable bolts 26. Openings are provided in substantially the middle of each barrel half to permit it to fit over the cylindrical body portion of the hub 1. The barrel 24 is made to fit the bearings 23 closely so that the blades 2 are held rigidly in position but may be turned about their longitudinal axes upon application of relatively large twisting force.

The blade may be made as shown in Fig. 4, with a flange structure 21a made separate from the blade, applied to the blade by means of a screw threaded joint, and locked in position by a lock nut device 27. The bearing 23, in this instance, is carried by the flange structure 21a, as shown.

The preferred method of manufacturing is to complete the blades with the exception of forming the flange 21. The shank of the blade is then heated to suitable temperature and the bearing 23 is slipped loosely over the root of the heated blade and moved on the shank to a position some distance from the end of the shank. The flange 21 is then formed by an upsetting process in the usual manner. The bearing 23 may be moved a considerable distance from the end of the shank, permitting the upsetting of the shank end without damage to the bearing. The flange 21 and the exterior of the shank are then machined to provide accurate seating surfaces after which the bearing 23 is moved down the shank to engage the seating surfaces. In case the blades used are of a light alloy requiring heat treatment after the upsetting operation to develop the full strength of the material, it is desirable to utilize bearings made of special steel of such characteristics that its hardness is not affected by the temperature used in heat treating the metal of the blade.

In the event that blades of the hollow steel type shown in Figs. 5 and 6 are used, the bearing 23 may be applied to the heated blade after the flange 21 has been formed, but just before the blade has been pressed to its final shape. After the machining operations on the blade have been performed, the blank may be heated to a temperature suitable for pressing it to final shape, and, while it is thus heated, the bearing 23 may be slipped over the tip end of the blank, as shown in Fig. 5, and moved to its normal position adjacent to the flange 21. The blank is then placed in a press and flattened in dies to the desired propeller shape, with the bearing 23 retained permanently in position as shown in Fig. 6.

After the bearing 23 has been applied to the blade shank, the bushing 11, which is preferably of steel, may be inserted. As shown, the exterior of the bushing 11 is tapered to fit a complementary tapered surface on the interior of the blade shank. Bushing 11 is made to fit accurately within the blade shank and is placed in position by first moderately heating the blade, as for instance by dipping the shank in hot oil, after which the sleeve 11 is pressed into the hollow root of the blade to bring its flange 14 into contact with the flange 21 of its blade root. After the blade cools, it shrinks into very firm engagement with the sleeve 11. However, in so

shrinking, the shank causes the sleeve 11 to contract, and some distortion may result. To correct this, the bearing surfaces 12 and 13 on the interior of the sleeve 11 are accurately lapped to their final dimensions.

These surfaces, as well as their complementary surfaces on the spider or stud 6, may be hardened by nitriding, or the like, to provide hard wearing surfaces. The bearing surfaces may be lubricated by graphite or similar material that may be placed in an annular chamber 28 adjacent to the annular bearing surfaces 16. The action of centrifugal force will feed the lubricant outwardly to lubricate the bearing surfaces 12 and 13.

As shown, the inner end of the sleeve 11 is reduced to what is known as a feather edge to permit it to flex with the blade during flight and thus avoid concentration of stress in the blade at the end of the sleeve. It is highly important in propeller construction to avoid all localization of stress. Fatigue cracks usually start from that condition.

By fitting the blades 2 in this manner very accurately and tightly on the studs 6 of the hub 1, wear between the blades and the hub is reduced to a minimum. During flight there is constant vibration in the propeller structure, particularly in the blades, and if looseness occurs between the blades and the hub, relative motion will result in destructive abrasion.

Although the blades 2 are fitted closely to the hub 1, it is possible by means of suitable apparatus that constitutes part of my invention, to turn the blades 2 for adjusting the pitch angle thereof, by means of an operating lug 31 formed integral with the flange 14 of the sleeve 11 and extending through a slot 32 in the barrel 24. The slot 32 is made of such length that the blade may be turned through a predetermined maximum angle of adjustment, but is prevented from turning to a position beyond the predetermined range. In a particular practical embodiment of my invention, a torque of substantially 2000 lb. inches is required to move the two blades 2 relative to the spider 6.

It is known that propeller blades in flight have a tendency to turn about their longitudinal axes to bring their major transverse axes into the plane of rotation of the propeller. This results from the twisting moments set up by the action of centrifugal force on the blades when the propeller is rotated. The tendency in flight is for the propeller to "lose its pitch".

This inherent tendency of the blades to turn towards the zero pitch position has heretofore been utilized for moving the blades to low-pitch position, and suitable apparatus provided for moving the blades to high-pitch position. Since the speed at which an airplane engine operates, tends to vary inversely with the pitch of the blade, in practicing the present invention the blade adjusting apparatus is constructed to utilize centrifugal force for increasing the pitch of the blade.

By constructing the apparatus in this manner, the tendency when the plane is in operation, is to move the blades to high-pitch position. If the engine speed becomes excessive for any reason, the centrifugal force acting to move the blades is increased and the blades may be moved to high-pitch position, thus checking the speed of the engine.

Inasmuch as the propeller is ordinarily set at high-pitch position during normal level flight of the airplane, it is desirable to utilize mechanism

carried by the propeller hub and constantly operative through centrifugal action to hold the propeller in the high-pitch position, rather than to depend upon externally operated mechanical or fluid pressure means for holding the propeller in high-pitch during normal flight.

To counteract the twisting moment resulting from the inherent effect of centrifugal force on the blades, and to provide operative twisting moment for moving the blades to high-pitch position, a pair of counterweights 41 is provided, pivotally mounted at one end on a collar 42 surrounding the hub 1. Each of the counterweights 41 is connected by a short link 43 to the operating lug 31 extending from the sleeve 11 of the blade. The link 43 is pivotally connected to the lug 31 by such means as a bolt 44, and is pivotally connected at its other end by a bolt 45 to the counterweight 41 at a point close to the center of rotation of the weight about its pivotal connection to the ring 42.

By reason of the short lever arm between the pivot axis of the counterweight and its connection to the link 43, a large mechanical advantage is obtained and the outer end of the counterweight moves through a relatively large angle in turning the blade from its low-pitch position to its high-pitch position. Consequently the counterweight 41 exerts a comparatively large force on the operating lug 31 of the propeller blade 2.

Although the counterweight is very light in proportion to the remainder of the propeller structure, it being made of aluminum or similar metal, the force exerted by it is sufficient to overcome the pitch-reducing moment of the blade resulting from centrifugal force and aerodynamic action, and to overcome the frictional resistance which results from the tight fitting manner in which the blade is mounted on the hub structure. The range of motion through which the counterweight travels in accomplishing movement of the blade from low-pitch position to high-pitch position is shown diagrammatically in Fig. 1. From this figure it may also be seen that the counterweights are shaped and pivoted in such manner as to cause their centers of gravity to move in an arc so positioned that the torque exerted by the action of centrifugal force is substantially constant for all pitch positions.

To overcome the action of the counterweights 41 to provide low-pitch position for starting, fluid pressure operating mechanism comprising a piston 51 is mounted on an extension of the propeller hub 1 and concentric with the axis of rotation of the propeller. The piston 51 is connected to the counterweights 41 by links 52 pivoted at one end to lugs 53 on the piston 51, and at their outer ends to the counterweights 41, by means of bolts 54, at a position a considerable distance from the point at which the counterweights are pivoted on the collar 42. In this manner a relatively long lever arm is provided for the connecting rod 52 in turning the counterweight, and consequently the piston 51 is enabled to move a considerable distance with a large mechanical advantage in turning the propeller from high-pitch to low-pitch position.

To actuate the piston, oil from the engine lubricating system is admitted through the hollow shaft 3. Inasmuch as the low-pitch position is utilized ordinarily only for brief periods, as for instance when the airplane is taking off, any leakage which may occur from the fluid actuated piston 51 is of little consequence.

The high-pitch and low-pitch positions of the

propeller blades may be determined by adjustable stop members that cooperate with lugs 55 on the surface of the piston 51. As shown in Figs. 2 and 3, the lugs 55 are provided with openings through which pass threaded studs 56 screwed into the barrel 24 at their inner ends and supported at their outer ends by a spacing ring 57. Pairs of lock nuts 58 and 59 are provided at the inner and outer ends of the studs 56, respectively, for engaging the lugs 55 to prevent further movement of the piston 51 after the blades have been turned to the predetermined angular position at either end of the range of operation.

To set the mechanism to provide predetermined high-pitch and low-pitch positions, the blades may be turned manually, by exerting force on the counterweights 41. For example, the blades may be first moved to a predetermined high-pitch position by pulling the counterweights outwardly until a scale 61 on the piston 51 that cooperates with a pointer 62 carried by the ring 57, indicates that the desired angular position has been reached. The lock nuts 58, which constitute the inner adjustable stops, may then be turned to engage the lugs 55 and there locked in position. By pushing the counterweights 41 inwardly, the blades may be turned to the low-pitch position, as indicated by the scale 61, and the lock nuts 59 turned to engage the lugs 55.

As shown in Figs. 1 and 2, the piston 51 is a cup-shaped member that operates on the outside of a cylinder or sleeve 65 threaded into and constituting an extension of the cylindrical portion 35 of the hub 1. To prevent leakage of fluid from the piston 1, the cylinder 65 is provided at its forward end, with a packing ring 66. Fluid under pressure for operating the piston 51 is conducted from the hollow shaft 3 to the forward end of the cylinder 65 by means of a tube or sleeve 67 secured by a coupling 68 in the end of the cylinder 65 and extending rearwardly into the end of the hollow shaft 3. At its inner end the sleeve 67 is provided with a packing ring 69 to prevent leakage 40 at the position in which it engages the inner surface of the hollow shaft 3.

As shown in the structure illustrated in Fig. 1, the opening in the forward portion of the hollow shaft 3 is separated by a partition 70 from the opening in the remainder of the shaft, which carries the lubricating oil under pressure in a well known manner. However, fluid pressure may be admitted to the forward portion of the shaft by way of openings 71 that extend radially from the hollow interior to the exterior of the shaft and communicate with an annular passageway in a sleeve 72 encircling the shaft 3 and supported in the forward end of the crank case 4.

Fluid pressure for the lubricating system and the propeller controlling system is generated by an engine driven pump 75, shown diagrammatically in Fig. 1, connected to be driven from the shaft 3. The pump 75 may be of any suitable type, such as an intermeshing gear pump, and it is supplied with oil through a supply conduit 76, leading from a container 77, which represents the sump of the engine crank case 4. From the pump 75 the oil is forced under pressure to the lubricating system, and through a pipe 78 and suitable passageways 79 in the crank case 4, to the annular chamber in the sleeve 72, from which it flows through the passageways 71 to the hollow shaft 3, and thence by the tube 67 to the piston 51.

For effecting operation of the variable pitch propeller the fluid system may be provided with

an adjustable spring pressed relief valve 82 similar to the standard relief valve ordinarily utilized in the pressure lubricating system of an engine. In operating a fluid pressure control system of this type the pilot may adjust the relief valve 82 to regulate the fluid pressure in the system and consequently to control the force exerted by the fluid upon the piston 51.

If the pilot wishes to move the propeller to low-pitch position, it is merely necessary to increase the pressure exerted by the spring pressed valve by turning an operating handle 83, thereby building up sufficient pressure to move the piston 51 outwardly in opposition to the force exerted by the counterweights.

When it is desired to move the propeller blades from low-pitch to high-pitch position, the pilot may reduce the pressure in the fluid system by turning the operating handle 83 in the opposite direction and thus reduces the force exerted by the piston 51 to such extent that centrifugal force acting on the counterweights 41 will overcome the fluid pressure force and move the blades to high-pitch position.

To provide for controlling the pitch of the propeller without changing the pressure in the engine lubricating system, a three-way valve 85 may be connected in the passage-way 79 through the crank case 4 in such manner as to admit the full pressure of the fluid system to the shaft 3. The valve may be turned to cut off the pressure from the oil pipe 78 and drain the oil from the piston 51. As shown in section in Fig. 1, the three-way valve 85 comprises a rotatable sleeve 86, open at one end and in communication with the annular passageway in the sleeve 72. At its side, the sleeve 86 is provided with a circular opening or port 87 that may be disposed in alignment with the passageway 79 in the crank case 4, as shown in the drawings, for admitting fluid pressure from the pump 75 to the hollow shaft 3.

When it is desired to move the propeller blades to low-pitch position the valve 85 is turned to the position shown for admitting fluid pressure to actuate the piston 51. To change the propeller to high-pitch position, the sleeve 86 may be turned to move the opening 87 out of alignment with the passageway 79, thus cutting off the pressure.

The oil may be drained from the piston 51 by turning the valve 85 farther to bring the port 87 into communication with a passageway 88, through which the oil may flow from the piston 51 into a tube 89 that returns it to the engine sump 77. The valve 85 may be operated from the pilot's cockpit by cables or other suitable means in well known manner.

In operating an airplane equipped with my controllable pitch propeller, after the engine is started and while the airplane is on the ground, fluid pressure is admitted through the hollow shaft 3 to move the piston 51 outwardly, thus turning the blades 2 to low-pitch position, as defined by the adjustable stops 59. The propeller is thus adjusted to permit development of maximum power of the engine in the heavy load of the take-off. After the plane has attained the position of level flight, the fluid pressure on the piston 51 is released and the counterweights 41, under the action of centrifugal force, turn the propeller blades to high-pitch position, bringing the lugs 55 or the piston 51 into engagement with the stops 58.

The forces acting to twist the blades during flight, and the relations of these forces to each

other with the propeller in different pitch positions are shown graphically in Fig. 11. In this figure the ordinates represent twisting moments about the blade axes in pound inches, and the abscissa represent the angular positions of the blades, which, of course, correspond to positions of the piston and of the counterweights. Corresponding positions of the piston, counterweights, and the propeller blade are indicated in Fig. 1 and along the abscissa in Fig. 11 by the corresponding reference characters A, B and C, respectively.

The lower dotted curve in the diagram, indicated by the reference character E, represents the twisting moment resulting from the inherent tendency of the blades to turn towards zero pitch position from the action of centrifugal force. The curve designated by the character F represents the twisting moment exerted upon the blades by the counterweights 41 and the connecting rods 52. It will be noted that this twisting moment is substantially double that inherent within the blades, and, as explained hereinbefore, acts in the opposite direction.

The counterweights 41 are preferably so shaped that the twisting moment F will, as nearly as possible, be uniform throughout the range of pitch adjustment, as shown by the curve F of Figure 11.

The solid line curve G represents the summation of the curves E and F, that is to say, the twisting moment F resulting from the counterweights minus the twisting moment E of the blades in the opposite direction. Thus the curve G indicates the resultant twisting moment tending to increase the pitch of the blades by the action of centrifugal force. The upper curve H represents the twisting moment applied to the blades by the fluid pressure acting upon the piston 51. This twisting moment is substantially twice as great as the twisting moment G resulting from centrifugal force, and consequently, when the oil pressure is applied to the piston 51, the twisting moment exerted by it upon the blades is sufficient to overcome the twisting moment resulting from centrifugal force and to provide a comparatively large additional force for overcoming the frictional resistance of the blades which results from the manner in which they are tightly fitted to the hub.

Likewise, it will be seen that when the oil pressure is released, the counterweights 41 in exerting the twisting moment F, overcome the twisting moment E exerted in the opposite direction by centrifugal force acting on the blades, and provide a large resultant moment represented by G for overcoming the frictional resistance of the blades to turn them to high-pitch position.

Under some circumstances, particularly those met with by military aircraft, it is desirable to have the pitch of the propeller automatically regulated to keep the engine speed substantially constant, and consequently to derive from the engine the maximum power of which it is capable at all times. To accomplish this, a system similar to that shown in Fig. 3 may be utilized, in which a governor mechanism 90 is disposed in the fluid system between the pump 75 and the hollow engine shaft 3 for governing the admission of pressure to the piston 51 in accordance with the speed of rotation of the engine and propeller.

The pump 75 may be the usual engine pump for supplying oil under pressure to the engine

lubricating system. From the pump 75 a pipe 91 leads to an annular chamber 92 surrounding the shaft 3, from which the oil passes through an opening 93 into the interior of the hollow shaft 3 at a position back of the partition 70, for lubricating the engine in the usual manner. Another pipe 94 extends from the pump 75 to the governor mechanism 90.

When the engine speed drops below a predetermined minimum, the governor is turned to the position shown in the drawings, in which position fluid pressure from the pipe 94 is permitted to pass through ports 95 into the interior of the governor, hence outwardly through ports 96 to a pipe 97 that leads to a sleeve 98 encircling the shaft 3 and having an annular chamber that communicates through an opening 99, to the interior of the hollow shaft 3 ahead of the partition 70.

If the engine speed is increased above a predetermined limit, the valve body 101 in which the ports 95 and 96 are located, will be turned in response to the increased speed to move the ports out of alignment with the openings leading to the pipes 94 and 97. As the valve member 101 continues to turn, ports 102 will be moved into communication with the pipe 97 to admit fluid from the propeller into the valve member 101, and ports 103 will be moved to communicate with a drain pipe 104, through which the oil may drain back to the sump 77.

The mechanism of the governor 90 is shown in detail in Figs. 7, 8, 9 and 10. The governor may be mounted in any convenient position in the airplane and is driven in synchronism with the engine by means of a flexible shaft, not shown, similar to the shaft ordinarily utilized on airplanes for driving the tachometer. The flexible shaft is connected in well known manner at the left end of the governor, as shown in Fig. 7, to the end of a shaft 110 that rotates, consequently, at a speed directly proportional to the speed of rotation of the engine. The governor mechanism is supported by and enclosed within a suitable casing 111 in which the shaft 110 is journaled.

Within the left end portion of the casing 111 are two governor weights 112, pivoted on a flange or wheel 113, which is keyed to and revolves with the shaft 110. As best shown in the cross sectional view in Fig. 10, the weights 112 are each provided with an arcuate rack, or segment of an internal gear 114 which engage, at diametrically opposite sides, a gear wheel 115 that is rotatably mounted on the shaft 110. Suitable coiled springs 116 are provided for holding the weights 112 at their innermost position when they are not being acted upon by centrifugal force. The racks 114 and the gear 115 are so arranged that when the weights 112 move from the inner position to their outer position, in the well known manner in which governors of the fly-ball type operate, the gear wheel 115 will be turned relative to the shaft 110 through an angle of substantially 30°.

As shown in Fig. 7, the gear wheel 115 is secured to a sun gear wheel 117 of similar size also rotatably supported on the shaft 110 to turn with the gear wheel 115. Meshing with the sun gear wheel 117 are three planetary pinions 118, best shown in Fig. 9, that are carried on a spider 119 rotatably mounted on the shaft 110. The planetary gears 118 also mesh, at their outer edges, with an internal or ring gear 120 which surrounds the spider 119 and is secured to the inner surface of the casing 111 in such manner that, during normal operation, the spider 119 will rotate within the housing in the direction of rotation of the 75

shaft 116 and at substantially one-half its speed.

Interposed between the planetary gears 118 in angular relation, and journalled on the opposite face of the spider 119 is another set of planetary gears 121. The planetary gears 121 mesh at their inner edges with a sun gear wheel 122 keyed to the shaft 110, and at their outer edges with a ring gear 123 carried by the valve member 101. The gear wheel 122 keyed to the shaft 110 corresponds in general to the gear wheels 115 and 117 journalled thereon, and the ring gear 123 on the valve 101 corresponds in general to the ring gear secured in the casing 111. If the shaft 110 is rotated slowly in such manner that governor weights 112 remain at their inner positions, the gear wheels 115, 117 and 122 all turn at the speed at which the shaft is rotated. Consequently, the spider 119 will progress in the same direction at one-half speed, and, inasmuch as the sun gears, planetary gears and ring gears correspond to each other, the ring gear 123 on the valve 101 will remain stationary and the planetary gears 121 will roll within it without changing the position of the valve 101.

If now we assume that the shaft 110 is held stationary and the governor weights 112 are moved outwardly by some external force, the gear wheel 115 will be turned relative to the shaft 110 through substantially 30°. Likewise, the sun gear wheel 117 will turn through 30°, which will cause the spider 119 to progress as a result of rotation of the planetary gears 118 within the ring gear 120. Inasmuch as the sun gear 122 is rigidly connected to the shaft 110 and therefore held stationary, the planetary gears 121 will be caused to rotate by the progressing motion of the spider 119, and consequently the ring gear 123 will be caused to turn through an angle of 30° in the direction opposite to that in which the gear wheel 115 turns as the result of movement of the governor weights 112.

As the ring gear 123 moves through this 30° angle, it causes the valve 101 to move from the position shown in Fig. 3, in which position the fluid pressure is admitted to the propeller mechanism, to the position in which the ports 103 come into communication with the pipe 104 for draining oil from the propeller mechanism to the engine sump.

The same relative motions take place when the shaft 110 is rotating and the governor weights 112 move under the action of centrifugal force. When the governor weights 112 rotate at a fixed radial position relative to the shaft 110, the ring gear 123 will remain stationary in a position relative to the ring gear 120, depending upon the position of the weights relative to the shaft. However, upon movement of the weights in radial direction relative to the shaft 110 the ring gear 123 will be turned relative to the ring gear 120 and the valve body 101 will be moved relative to the casing 111.

For regulating the speed at which the governor will function to change the position of the valve 101, an operating lever 130 is provided at the right end of the governor, to increase or decrease the pressure exerted by springs 131, which oppose rotation of the valve 101. As best shown in Fig. 8, the springs 131 are each connected at one end by means of a pivot pin 132 to a disk or plate 133 secured to the valve body 101. At their other ends the springs 131 are pivoted by pins 134 at the ends of an arm 135 which is keyed to a stub shaft 136 that may be actuated by the operating lever 130. As may be seen in Fig. 8, when

the shaft 136 is turned clockwise, the springs 131 will be compressed and will exert a greater force tending to oppose rotation of the plate 133 and of the valve body 101. Consequently, the engine speed at which the propeller will be automatically changed from low pitch to high pitch position is increased.

By moving the operating lever 130 to turn the shaft 136 counterclockwise, the force exerted by the springs 131 will be decreased, hence the rate of revolution at which the governor weights 112 will become effective to turn the valve 101 is reduced, and the propeller will move from low pitch to high pitch position at lower engine speed. Consequently, by means of the lever 130, the speed of the engine may be regulated by changing the speed at which rotation of the valve occurs.

Although I have described in detail certain specific embodiments of my invention it is to be understood that the particular structures shown and the descriptions thereof are for the purpose only of disclosing complete and workable apparatus and it will be obvious to others skilled in the art that various modifications in the details of construction of the propeller and particularly in the auxiliary devices as valves and governing mechanism may be made without departing from the spirit and scope of the invention defined in the appended claims.

What I claim is:

1. A controllable pitch propeller for aircraft, comprising a hub having radially extending arms, propeller blades rotatably journalled around the arms, fluid pressure operated means to move the blades to decrease their pitch at will, and to overcome a contrary tendency of centrifugal force tending to increase the pitch of the blades, and counterweights mounted to revolve with the propeller and operative automatically to increase the pitch of the blades by the action of centrifugal force on the weights when the fluid pressure means is not operative.

2. A controllable pitch propeller for aircraft, comprising a hub structure, blades rotatably mounted on the hub, movable counterweights pivoted on the hub, linkage connecting the counterweights to the blades to effect change in the pitch of the blades in one direction by the action of centrifugal force on the counterweights, and manually controllable fluid-pressure operated means adapted to change the pitch in the other direction by overcoming the force of the counterweights.

3. In aircraft driving apparatus, in combination, an engine shaft, a propeller driven by the engine shaft, constantly-operative means comprising centrifugally driven counter-weights tending to increase the pitch of the propeller in flight, an engine-operated fluid pump, a fluid system connected to the pump and operative at will to decrease the pitch of the propeller, and governing means responsive to the engine speed for automatically controlling the fluid system and thereby the pitch of the propeller.

4. In aircraft driving apparatus, in combination, an engine, a propeller driven by the engine, means comprising movable counter-weights constantly operative during flight tending to increase the pitch of the propeller, an engine-operated fluid pump, and a fluid system connected to the pump and operative at will to decrease the pitch of the propeller by overcoming the effects of the counter-weights.

5. In aircraft driving apparatus, in combination, an engine, a propeller driven by the engine,

- means constantly operative by centrifugal force during flight tending to increase the pitch of the propeller, an engine-operated fluid pump, a fluid system connected to the pump and operative at will to overcome said first mentioned means to decrease the pitch of the propeller, and a governor responsive to the engine speed for controlling the pressure in the fluid system to decrease the pitch of the propeller with decrease of the engine speed.
5. A controllable pitch propeller comprising a hub portion, blades journaled on the hub, counterweights carried by the hub, means connecting the counterweights to the blades to turn them under the action of centrifugal force in one direction, a fluid-pressure actuated piston, and means connecting the piston to the counterweights to overcome the action of centrifugal force thereon for turning the blades in the other direction.
10. 6. A controllable pitch propeller comprising a hub portion, blades journaled on the hub, counterweights carried by the hub, means connecting the counterweights to the blades to turn them under the action of centrifugal force in one direction, a fluid-pressure actuated piston, and means connecting the piston to the counterweights to overcome the action of centrifugal force thereon for turning the blades in the other direction.
15. 7. A controllable pitch propeller for engine driven airplanes, comprising a hub, propeller blades journaled on the hub for pitch-adjusting rotation about their individual axes, adjustable stops to limit the movement of the blades in either direction to define a low-pitch and a high-pitch position, centrifugally-actuated means comprising counter-weights carried by the hub for moving the blades during flight to the high-pitch position, and controllable means driven by the engine for overcoming the action of the centrifugally actuated means to move the blades to the low-pitch position.
20. 8. In a controllable pitch propeller for aircraft, comprising a hub structure, blades rotatably mounted on the hub, movable counterweights pivoted on the hub, and linkage connecting the counterweights to the blades at a point intermediate the free and pivoted ends of the counterweights to effect change in the pitch of the blades in one direction by the action of centrifugal force on the counterweights, said counterweights and linkage being so shaped and connected that the torque exerted to turn the blades is substantially constant throughout the range of movement of the counterweight, and means to overcome the effect of the counterweights at will.
25. 9. In a controllable pitch propeller for aircraft, comprising a hub, blades mounted on the hub and rotatable on their longitudinal axes for pitch adjustment, levers pivotally attached to the hub at one end, the free ends of the levers constituting counterweights, intermediate parts of the levers being connected to linkage attached to the blades, the lever being curved and proportioned and the linkage being arranged so that as centrifugal force acting on the weight increases with outward movement of the weight, the leverage effective to turn the blades varies inversely as the increase of centrifugal force due to position of the weight, such construction being adapted to apply substantially uniform turning moment to increase the pitch of the blade at all positions of the counterweights, and means to overcome the effect of the counterweights to restore the blades to low-pitch position at will.
30. 10. A controllable pitch propeller comprising a hub, propeller blades journaled on the hub for pitch-adjusting rotation about their individual axes, adjustable stops to positively limit the movement of the blades in either direction to define a low-pitch and a high-pitch position, positive stops to limit the maximum movement of the blades in either direction, and means for moving the blades during flight.
35. 11. A controllable pitch propeller comprising a hub portion having tapered integral extensions with a lubricant retaining pocket in the surface thereof, blades journaled on the extensions, counter-weights carried by the hub, means connecting the counter-weights to the blades to turn them under the action of centrifugal force in one direction, a fluid pressure actuated piston, and means connecting the piston to the counterweights to overcome the action of centrifugal force thereon for turning the blades in the other direction, the blades having a hardened steel interior bearing constituting the portion that is journaled on the hub extensions.
40. 12. A variable pitch propeller comprising a plurality of blades, means for rotating said blades, means responsive to centrifugal force for increasing the pitch of the blades, and fluid pressure operated means opposing the operation of said centrifugally responsive means for decreasing the pitch of the blades.
45. 13. A variable pitch propeller comprising a plurality of blades, means for rotating said blades, means responsive to centrifugal force for increasing the pitch of the blades, and fluid pressure operated means for controlling the operation of said centrifugally-responsive means.
50. 14. A variable pitch propeller comprising a plurality of blades, means for rotating said blades, means responsive to centrifugal force for increasing the pitch of the blades, and other means for decreasing the pitch of said blades including a fluid pressure operated member operatively connected with said centrifugally-responsive means and acting in opposition to said centrifugally responsive means.
55. 15. A variable pitch propeller comprising a plurality of blades, means for rotating said blades, means responsive to centrifugal force for increasing the pitch of the blades, fluid pressure operated means for decreasing the pitch of the blades, and means for controlling the operation of the fluid pressure operated means.
60. 16. A variable pitch propeller comprising a plurality of blades, means for rotating said blades, means responsive to centrifugal force for increasing the pitch of the blades, fluid pressure operated means for decreasing the pitch of the blades, and a governor responsive to changes in the rate of rotation of said blades for controlling the operation of said fluid pressure operated means.
65. 17. A variable pitch propeller comprising a plurality of blades, means for rotating said blades, means responsive to centrifugal force for increasing the pitch of the blades, fluid pressure operated means for controlling operation of said centrifugally responsive means, and means for controlling the operation of said fluid pressure operated means.
70. 18. A variable pitch propeller comprising a plurality of blades, means for rotating said blades, means responsive to centrifugal force for increasing the pitch of the blades, fluid pressure operated means for controlling the operation of said centrifugally responsive means, and a governor responsive to changes in the rate of rotation of said blades for controlling the operation of said fluid pressure operated means.
75. 19. A variable pitch propeller comprising a plurality of blades, means for rotating said blades, means responsive to centrifugal force for varying the pitch of said blades, means operable in accordance with the increase in volume of a fluid container for controlling the operation of said centrifugally responsive means, and means for

controlling the increase in volume of said fluid container.

20. A variable pitch propeller comprising a plurality of blades, means for rotating said blades, means responsive to centrifugal force for varying the pitch of said blades, means operable in accordance with the increase in volume of a fluid container for controlling the operation of said centrifugally responsive means, and means for controlling the increase in volume of said fluid container, said last named means including a governor responsive to changes in the rate of rotation of said blades.

21. In combination with a rotatable shaft, a propeller hub drivably connected thereto, a plurality of propeller blades rotatably mounted on said hub, means for rotating said blades on said hub to vary the pitch thereof, said means including a fluid operated expandible chamber device, and means including a plurality of manually adjustable and independently acting devices for selectively predetermining the extent of operation of said fluid operated expandible chamber.

22. A controllable pitch propeller comprising a plurality of blades, means for rotating said blades, means responsive to centrifugal force to effect changes in the pitch of the blades in one direction by the action of centrifugal force on said means, and manually controllable fluid pressure operated means adapted to change the pitch of the blades in the other direction by overcoming the force of the means responsive to centrifugal force.

23. A controllable pitch propeller for aircraft, comprising a hub structure, blades rotatably mounted relative to the hub, counterweights connected to the blades to effect a change in the pitch of the blades in one direction by the action of centrifugal force on the counterweights and manually controllable fluid pressure operated means adapted to change the pitch in the other direction by overcoming the force of the counterweights.

24. A controllable pitch propeller for aircraft, comprising a hub structure, blades rotatably mounted relative to the hub, counterweights connected to the blades to effect change in the pitch of the blades in one direction by the action of centrifugal force on the counterweights, and controllable fluid pressure operated means adapted to change the pitch in the other direction by overcoming the force of the counterweights and governing means responsive to the speed of rotation of said propeller for automatically controlling the fluid pressure operated means.

25. A controllable pitch propeller comprising a hub portion, blades journaled on the hub, counterweights connected to the blades to turn them under the action of centrifugal force in one direction, a fluid pressure actuated piston and means connecting the piston to the counterweights to overcome the action of centrifugal force thereon for turning the blades in the other direction.

26. In aircraft driving means, the combination of an engine shaft, a propeller driven thereby, an engine-operated fluid pump, a fluid conducting system, including fluid pressure means, connected from the pump to the propeller, and counterweights and connections operated by centrifugal force to increase the pitch of the propeller when the fluid pressure means is inactive, said fluid conducting system operative at will to overcome the effect of centrifugal force to decrease the pitch of the propeller.

27. A controllable pitch propeller, comprising a hub portion, blades journaled relative to the hub, counterweights connected to the blades to turn them in one direction under the influence of centrifugal force, fluid pressure actuated piston and means connecting the piston to the blades to overcome the action of centrifugal force and turn the blades in the other direction.

FRANK W. CALDWELL.
